(57) **CLAIM**

The ornamental design for a safety apparatus, as shown and described.

DESCRIPTION

FIG. 1 is a front view of a safety apparatus showing our new design, with the glasses in a lowered position;

FIG. 2 is a right side view thereof;

FIG. 3 is a back view thereof;

FIG. 4 is a top view thereof;

FIG. 5 is a bottom view thereof;

FIG. 6 is a perspective view thereof;

FIG. 7 is another perspective view thereof;

FIG. 8 is a side view thereof, with the glasses in a partially raised position; and,

FIG. 9 is a side view thereof, with the glasses in a fully raised position.

1 Claim, 9 Drawing Sheets
